UNITED STATES PATENT OFFICE

169,564

CASTER BRACKET

Edward H. Schultz, Jr., Chicago, Ill., assignor to
The Nagel-Chase Manufacturing Company,
Chicago, Ill., a corporation of Illinois

Application May 24, 1952, Serial No. 19,868

Term of patent 14 years

(Cl. D10—9)

To all whom it may concern:

Be it known that I, Edward H. Schultz, Jr., a citizen of the United States, residing at Chicago, county of Cook, State of Illinois, have invented a new, original, and ornamental Design for a Caster Bracket, of which the following is a specification, reference being had to the accompanying drawing, forming a part thereof.

Fig. 1 is a perspective view of a caster bracket, showing my new design;

Fig. 2 is a side elevational view;

Fig. 3 is a top plan view,

I claim:

The ornamental design for a caster bracket, substantially as shown.

EDWARD H. SCHULTZ, JR.
